SEASONAL TRIMMING FOR A MAILBOX OR SIMILAR ARTICLE

Jerome Marrow, 40 E. 66th St.,
New York, N.Y. 10017

Filed Mar. 15, 1972, Ser. No. 235,098

Term of patent 3½ years

Int. Cl. D11—05

U.S. Cl. D29—1 B

FIG. 1 is a front elevational view of a seasonal trimming for a mailbox or similar article showing my new design;

FIG. 2 is a rear elevational view thereof with the slidably mounted garland in an alternate position.

I claim:

The ornamental design for a seasonal trimming for a mailbox or similar article, as shown and described.
